DESIGN FOR A COMBINATION FIGURINE
AND BEVERAGE SET

Zilpah Corn Gifford, Oakland, Calif.

Application April 28, 1947, Serial No. 138,658

Term of patent 7 years

(Cl. D44—24)

To all whom it may concern:

Be it known that I, Zilpah Corn Gifford, a citizen of the United States of America, residing at Oakland, in the county of Alameda and State of California, have invented a new, original, and ornamental Design for a Combination Figurine and Beverage Set, of which the following is a specification, reference being had to the accompanying drawing, forming a part thereof.

Fig. 1 is a perspective view of a combination figurine and beverage set, showing my new design;

Fig. 2 is a perspective view of the upper body portion of the figurine removed from the bottom support; and

Fig. 3 is a perspective view of the bottom support with the skirts of the figurine being shown in raised position.

I claim:

The ornamental design for a combination figurine and beverage set, substantially as shown.
ZILPAH CORN GIFFORD.
